UNITED STATES PATENT OFFICE.

TOM WILLIAMS, OF MARYSVILLE, KANSAS.

ROTARY SPADER.

1,300,083.

Specification of Letters Patent.

Patented Apr. 8, 1919.

Application filed November 6, 1917. Serial No. 200,558.

To all whom it may concern:

Be it known that I, TOM WILLIAMS, a citizen of the United States, residing at Marysville, in the county of Marshall and State 5 of Kansas, have invented certain new and useful Improvements in Rotary Spaders, of which the following is a specification.

This invention relates to rotary spaders and has more especial reference to improvements in the types of cultivators shown and 10 claimed in my co-pending U. S. application Serial No. 73,145.

The invention has for its dominant object to provide a rotary spader having novelly 15 mounted cultivating spades, the spades being mounted in a manner to cause engagement of the same with the soil, upon rotation of the drum, and to allow movement of the drum thereover in order that the 20 same will be disengaged from the soil, thereby properly spading or turning the soil and preventing the abnormal straining of the spades or drum.

Another and equally important object of 25 the invention is to provide the spade with spring buffering means, whereby all shock incident to the relative adjustment of the spades previous to their engagement with the soil will be absorbed and the said spades prop- 30 erly spaced.

The foregoing together with additional advantageous details and arrangement of parts of the preferred embodiment of my invention will be clear from the specific description hereinafter contained, when read 35 in connection with the accompanying drawings forming part thereof, wherein said embodiment of the invention is illustrated for the purpose of facilitating a full under- 40 standing of the present improvements.

In the drawings:

Figure 1 is a side elevation of the improved rotary spader showing the same mounted upon the drive axle of a motor 45 driven vehicle; and

Fig. 2 is a rear elevation of one of the spades showing the manner in which the same is secured to the drum, it being noted that the drum is fragmentarily shown in 50 section.

Similar characters of reference refer to similar parts throughout the several views of the drawings.

Having more particular reference to the 55 drawings, M indicates the motor driven vehicle to which the improved spader is at-

tached, the said vehicle being provided with rear wheels W mounted in suitable bearings in proximity of the drive axle of the same.

Mounted on one end of the drive axle of 60 the motor vehicle M is a drum 1 serving as means for carrying the spades, presently referred to.

A plurality of spading elements 2 are provided and are arranged upon the free 65 ends of substantially U-shaped arms 3, the lateral extremities of which are pivotally connected to the opposite sides of the drum 1 by means of bolts 4 passing therethrough. The bases of the U-shaped arms 3 are aper- 70 tured and receive rivets 5 therethrough, which rivets are in turn passed through the spading elements 2, U-shaped bolts 6 are also passed through the spading elements 2 and about the intermediate portions of the 75 U-shaped arms 3, thereby securely fastening the spading elements to the said arms. In this connection, it is to be noted that the intermediate portions of the U-shaped arms 3 are bent, thus, arranging the outer ends 80 of the same at angles to the inner ends or portions thereof.

Buffer elements comprising spring arms 7 having certain ends curved upon themselves as at 8 and the remaining ends bent at substantially right angles as at 9 and secured to the various spading elements 2 by means of bolts or rivets 10 and U-shaped clips 11 serve as means for maintaining the spading 85 elements 2 in proper spaced relation in order 90 that the same will be properly engaged with the soil; also, absorbing the shock incident to the relative adjustment of the spading elements 2 and during their movement through the soil. 95

From the foregoing, it will be readily understood that the spading elements 2 due to their connection with the drum 1 will be caused to engage the soil over which the motor driven vehicle M is driven. Upon 100 further rotation of the drum 1, the same will be permitted to move over the spading elements engaged with the soil and then as a consequence, the said elements will be caused to become disengaged from the soil, thereby 105 throwing the soil upward and backward and preventing undue straining of the spading elements or the arms carrying them or the drum to which the arms are pivotally secured. Further, it is to be also noted that 110 the spading elements subsequent to their engagement with the soil rest upon the pe-

riphery of the drum 1 during the upward movement thereof. However, upon the downward movement of the same, they drop forward by gravity and assume positions as shown in Fig. 1; the spring buffers serving as means for maintaining them in spaced relation and also absorbing all shock incident to the relative adjustment of the elements.

10 It is to be also noted, that inasmuch as the rotary spader is mounted upon the drive axle of the motor driven vehicle M, the same will serve as traction means for the vehicle, driving the same over the surface of the 15 soil to be cultivated thereby.

Manifestly, the construction shown is capable of considerable modification and such modification as is within the scope of my claims, I consider within the spirit of my 20 invention.

I claim:

1. In a rotary spader, a drum, arms pivotally engaged with the drum, spades carried by the arms, and means carried by said spades and coacting with the adjacent spades and said drum for maintaining said spades in properly spaced relation during the rotation of the drum and the swinging of the arms and for absorbing all shocks 30 incident to the relative adjustment of the spades.

2. In a rotary spader, a drum, arms bent intermediate their ends pivotally engaged with the opposite sides of said drum, spades 35 carried by said arms, and resilient members carried by the spades and contacting with the adjacent spades at times and at other times with the drum for maintaining said spades in properly spaced relation during

the rotation of the drum and the swinging 40 movement of the arms, and also designed to coact with the drum for absorbing all shocks incident to the relative adjustment of the spades.

3. In a rotary spader, a drum, arms pivotally engaged with the drum, spades carried by said arms, and spring buffers engaged with the spades and projecting rearwardly therefrom and serving as a means for coacting with the drum and the adjacent 50 spades for maintaining said spades in properly spaced relation during operation of the device and also coacting with the drum for absorbing all shocks incident to the relative adjustment of the spades. 55

4. In a rotary spader, a drum, arms bent intermediate their ends pivotally engaged with the opposite sides of the drum, spades carried by said arms, and buffer springs secured to the spades and projecting rearwardly therefrom. 60

5. In combination with the drive axle of a motor driven vehicle, a drum mounted thereon, arms pivotally engaged with the drum, spades carried by the arms, and spring buffers connected to the rear faces and near the inner edges of the spades and projecting rearwardly therefrom and coacting with the drum and the adjacent spades for arranging the spades in positions to 70 cause the proper engagement and disengagement of the spades with and from the soil and also designed to absorb all shocks incident to the relative adjustment of the spades. 75

In testimony whereof, I affix my signature hereto.

TOM WILLIAMS.
